DESIGN FOR A CABINET FOR AMUSEMENT GAME APPARATUS

Walter A. Tratsch, Chicago, Ill.

Application September 11, 1936, Serial No. 64,809

Term of patent 3½ years

To all whom it may concern:

Be it known that I, Walter A. Tratsch, a citizen of the United States and a resident of Chicago, in the county of Cook and State of Illinois, have invented a new, original, and ornamental Design for a Cabinet for Amusement Game Apparatus, of which the following is a specification, reference being had to the accompanying drawing, forming a part thereof, and in which:

Fig. 1 is a perspective view of a cabinet for amusement game apparatus, showing my new design, and

Fig. 2 is a side view of the same.

I claim:

The ornamental design for a cabinet for amusement game apparatus, as shown.

WALTER A. TRATSCH.
